Fig. 1

UNITED STATES PATENT OFFICE.

CHARLES C. ABBOTT, OF PITTSFIELD, MASSACHUSETTS, ASSIGNOR TO TRIUMPH VOTING MACHINE COMPANY, OF PITTSFIELD, MASSACHUSETTS, A CORPORATION OF NEW JERSEY.

MULTI-INDORSEMENT MECHANISM.

1,054,075.

Specification of Letters Patent. Patented Feb. 25, 1913.

Application filed May 16, 1912. Serial No. 697,668.

To all whom it may concern:

Be it known that I, CHARLES C. ABBOTT, a citizen of the United States, residing at Pittsfield, county of Berkshire, State of Massachusetts, have invented an Improvement in Multi-Indorsement Mechanism, of which the following is a specification.

This invention has for its object to provide an attachment for voting machines, which may be readily applied and removed, for the purpose of preventing more than one vote being cast for a candidate whose name appears on a plurality of party tickets and is an addition to and carrying forward of the invention described and claimed in my pending application, Serial Number 657,924, filed November 1, 1911.

The invention is limited in its use to a condition in group voting in which the same person has been nominated or indorsed for an office in a group by two or more parties and his name appears on a plurality of party tickets, *i. e.* in a plurality of party lines. The term "group voting" is used in its ordinary sense. For example, a plurality of officers are to be elected by a plurality of parties, each of which nominates one or more candidates. A voter may cast his votes for the nominees of one party or may cast one vote for a nominee of a plurality of parties, or may otherwise split up his vote but can only cast as many votes as there are offices to be filled. If the conditions require a group of three office columns only, the attachment is made to correspond. If more office columns are liable to be included, the attachment is made larger. Any attachment may be used for a group of less office columns than its maximum, or two attachments may be used should conditions require.

In the laws relating to group voting, it is usually required that a candidate's name shall appear in the group in the order of his nomination. A candidate might, therefore, be nominated as the first of the group by one party and indorsed as the second, or other member of the group, by another party, which would place that candidate's name in two office lines of the group. My present invention provides mechanism supplemental to the mechanism of my said

former application referred to, by which it is rendered impossible to cast two votes for any member of a group, no matter in how many office lines his name may appear or in what positions in the several lines.

In the accompanying drawing forming a part of this specification, Figure 1 is an elevation partly broken away, illustrating my novel mechanism as seen from the front of the machine, the side of the machine which the voter approaches being called the front of the machine, and the voting face the back; Fig. 2 a side elevation, as seen from the right in Fig. 1; and Fig. 3 is a section on the line 3—3 in Fig. 1.

10 denotes horizontals of the machine, 11 the shafts of voting members and 14 counter dogs.

The present invention comprises, as in my said former application referred to, a plurality of strips, each made up of a plurality of sections 15, adapted for use in connection with columns of voting members 75 and two-armed locking dogs 16 which are removably attached to the voting member shafts and are retained in position thereon by strip sections lying on opposite sides of the locking dogs. The strip sections are 80 made longer than the distance between two of the voting member shafts and are provided near their ends with elongated openings 17 through which the shafts pass freely. At each end of each section on its inner face 85 is a cross piece 18, the ends of which are bent upward and inward to form undercut ways 19. The sides of the sections are beveled backward and inward from their inner faces as at 20, the beveled edges of each section 90 sliding freely in the ways of other sections. In order to make the sections readily separable from each other, the bevels are cut away on both sides for a short distance at their mid-length, as at 21, so that when two 95 engaged sections are moved inward longitudinally the ways will slide along the bevels until the cut-away portions are reached, when the sections may be readily separated from each other as the inner ends of the 100 ways will pass freely over the cut-away portions, but when the sections are moved outward longitudinally the ways will ride over the bevels and thus lock the two sections

against separation except in the manner just described. Each cross piece has at its mid-length a lug 22, which may be formed by striking the metal inward, which is 5 adapted to engage a longitudinal slot 23 in another section, there being a lug at each end of each section and two slots in each section adapted to be engaged by the lugs of the contiguous sections.

10 It will of course be obvious that in case the separable feature of the sections is not required, cut-away portions 21 may be omitted and the sections when once secured together remain so, the limit of longitudinal 15 movement being determined by the engagement of the lugs with the ends of the slots.

The locking dogs 16 are simply elongated plates of metal, rounded at the ends for smoothness in operation and are each provided with a non-circular central opening 24 which receives a voting member shaft freely but prevents rotation of the locking dog thereon. The shafts are shown as grooved on opposite sides and the openings 25 in the locking dogs as corresponding therewith. The locking dogs are free to slide on the shafts and in assembling are placed between two sections of the multi-indorsement strip. When a strip is in position 30 for use on a column of voting members, the sections are suspended from the locking dogs on the shafts of the voting members included in the assemblage, (meaning the voting numbers pertaining to any 35 single candidate), the upper cross pieces of the sections resting upon the locking dogs which are now lying horizontally or approximately so. When an intermediate voting member is not included in an assemblage, no locking dog is placed on the shaft thereof and the section below is suspended through the engagement of the upper lug on the lower section with the lower end of the lower slot in the section above it, said 40 slot being in practice approximately in alignment with the edge of a locking dog in the horizontal position. The locking dogs and strip sections are retained loosely upon the voting member shafts in any suitable manner, as by cotter pins 27. The sections are 45 interchangeable and the entire structure when assembled is of very loose construction but forms a positive lock when a voting member is operated and the locking dog 50 thereon is turned to the vertical, or approximately vertical, position.

The added feature of novelty of the present invention consists of a wedge system comprising two rows of oppositely extending 55 interengaging swinging wedges, preferably provided with convex operative faces, as shown. The wedges of the upper set are indicated by 28 and the wedges of the lower set by 29. These wedges are carried between plates 30 which are retained in posi-

tion by spacing rivets 31, the wedges swinging freely between the plates. The set of wedges and the plates by which they are carried form an attachment complete in itself. At the lower ends of the plates are holes 32 which receive the voting member shafts. The plates, and with them the wedges, may be placed upon any line of voting members that may be necessary to meet the requirements of use. The wedges of the lower set 70 swing upon pivots 33 near the lower edges of the plates and extend upward, and the wedges of the upper set extend downward and are provided with bearing lugs 34 which engage notches 35 in the upper edges of the plates, one end of each lug being provided with a hook 36 which is adapted to engage a slot 23 in one of the sections.

The operation is as follows: The drawing shows portions of four party lines and five office columns, to three of which multi-indorsement strips have been applied, it being of course immaterial how many of these strips are used. The party lines are counted from the top downward and the office columns from left to right, as seen from the back or voting face of the machine and from right to left, as seen in Fig. 1. The voting member shaft in the first office column (from right to left in Fig. 1) of the first party line is shown as provided with a locking dog, likewise the voting member shaft in the third office column of the second party line, and the voting member shaft in the fifth office column of the third party line. 85 For convenience in description, one voting member shaft only is shown in the voted position, to wit: the voting member shaft in the first party line of the first office column, the voted position of the locking-dog being indicated by dotted lines. It is required that a locking dog be placed upon the shaft of each voting member corresponding with a candidate who has been nominated or indorsed by a plurality of parties and that 90 strip sections enough be used to provide a section on each side of each locking dog. The locking dogs normally lie in the horizontal position, as shown, and the voting movement swings them to a vertical or approximately vertical position. The amount of longitudinal movement of the sections permitted by lugs 22 and slots 23 is just 95 enough to permit one locking dog only in an assemblage to be turned to the voting position; i. e. given a quarter turn, more or less. The locking dogs above an operated locking dog will closely engage the upper cross pieces of sections, which cannot move upward, and the locking dogs below the operated locking dog will closely engage the lower cross pieces of sections which cannot move downward, thus locking all the sections against movement and consequently locking all voting members in the assem- 100 105 110 115 120 125 130

blage, that is all voting members in that column upon whose shafts locking dogs have been placed.

The operation of my novel multi-indorsement strips is set forth more at length in my said former application referred to and is not thought to require fuller description in this specification.

In carrying out my present invention, the 10 lower section of each strip is connected to one of the upper wedges 28 by engaging the hook on the wedge with the lower slot 23 in the section. When, therefore, a locking dog is turned to the operated position 15 through the operation of a voting member, the effect will be to raise all that portion of the multi-indorsement strip which lies below the operated locking dog. The lower section raises the wedge carried thereby 20 from the dotted position shown at the right in Fig. 1 to the full line position. Spacing rivets 31 are provided in position to act as bearings for the end wedges of the system as clearly shown. The wedges of the 25 system have just enough play to permit one wedge only to be raised, the entire system being locked, *i. e.* its slack all taken out, by the raising of any wedge. The operation of a voting member therefore takes all the 30 slack out of the corresponding multi-indorsement strip and in addition thereto causes a locking of the wedge system. The locking of the sections of the strip prevents the possibility of another vote being cast for 35 a candidate in the same office column and the locking of the wedge system prevents another vote being cast for him in any office column included in the group.

Having thus described my invention, I 40 claim:

1. A multi-indorsement restricting device comprising two-armed locking dogs, for the purpose set forth, a strip consisting of sliding sections lying on opposite sides of the 45 locking dog, each section being provided with means adapted to be engaged by a locking dog to lock the sections against longitudinal movement, swinging wedges suspended from the lower sections, other swinging 50 wedges inter-engaging therewith, and bearings for the end wedges of the system.

2. A device of the character described comprising two-armed locking dogs, for the purpose set forth, a strip consisting of sections 55 having limited longitudinal movement and adapted to receive locking dogs between them, cross pieces on the sections adapted to be engaged by the locking dogs, swinging wedges suspended from the lower sections, 60 other swinging wedges interengaging therewith and bearings for the end wedges of the system.

3. A device of the character described comprising two-armed locking dogs, for the 65 purpose set forth, a strip consisting of sec-

tions adapted to receive locking dogs between them, each section having openings, longitudinal slots, cross pieces and lugs, for the purpose set forth, swinging wedges suspended from the lower sections, other swinging 70 wedges interengaging therewith and bearings for the end wedges of the system.

4. The combination with voting member shafts, two-armed locking dogs carried thereby and a strip consisting of sliding sections 75 having cross pieces adapted to be engaged by the locking dogs, of swinging wedges suspended from the lower sections, other swinging wedges inter-engaging therewith, and bearings for the end wedges of 80 the system.

5. The combination with voting member shafts, two-armed locking dogs carried thereby, a strip consisting of sliding sections having means for engagement by the 85 locking dogs and means for connecting the sections leaving them free to slide longitudinally, of swinging wedges suspended from the lower sections, other swinging wedges interengaging therewith, and bearings for 90 the end wedges of the system.

6. The combination with a voting member shaft, a multi-indorsement strip comprising sliding sections having longitudinal movement and provided with cross pieces 95 at each end, of a locking dog carried by the voting member shaft and adapted to engage the upper and lower cross pieces of lower and upper sections respectively, a swinging wedge suspended from the lower section, 100 other swinging wedges interengaging therewith and bearings for the end wedges of the system.

7. The combination with a two-armed locking dog and a multi-indorsement strip 105 comprising sliding sections having longitudinal slots, cross pieces at their ends which are engaged by the locking dogs and are bent to form ways for contiguous sections and lugs projecting from the cross pieces 110 and engaging longitudinal slots in contiguous sections, of a swinging wedge suspended from the lower section, other swinging wedges interengaging therewith and bearings for the end wedges of the system. 115

8. In a voting machine, the combination with voting member shafts and two-armed locking dogs carried thereby, of multi-indorsement strips comprising sliding sections having means for engagement by the locking dogs, swinging wedges connected to the lower sections and other swinging wedges interengaging therewith, whereby the casting of more than one vote for a candidate whose name appears on a plurality of tickets 120 is prevented without regard to the order of nomination on the several tickets.

9. The combination with a multi-indorsement strip comprising sliding sections and a two-armed locking dog whose ends are 125

4
adapted to engage upper and lower sections, of a wedge system consisting of oppositely extending interengaging swinging wedges, one of which is connected to the lower section of the strip.

- 5 10. The combination with a multi-indorsement strip comprising sliding sections, of a wedge system consisting of plates having notches in their upper edges, downwardly extending swinging wedges having lugs engaging the notches, one of said wedges being connected to the strip, and upwardly extending interengaging wedges pivoted between said plates.
- 10 15. 11. The combination with a multi-indorsement strip comprising sliding sections, of a wedge system consisting of plates having notches in their upper edges, downwardly extending swinging wedges having lugs engaging the notches, the lugs upon one side forming hooks adapted to engage the strip, and upwardly extending interengaging wedges pivoted between the plates.
- 20 12. The combination with a multi-indorsement strip comprising sliding sections having lug and slot connections, of a wedge system consisting of plates having notches in their upper edges, downwardly extending swinging wedges having lugs engaging the

notches, the lugs upon one side comprising hooks adapted to engage the slot in the lower section of the strip and upwardly extending interengaging wedges pivoted between the plates.

13. In a voting machine, the combination with a multi-indorsement strip comprising sliding sections and locking dogs adapted to engage the sections, of a wedge system consisting of plates, downwardly extending swinging wedges having lugs loosely engaging the plates and means for engaging the lower sections of the strips, upwardly extending inter-engaging wedges pivoted between the plates and bearings for the end wedges of the system.

14. In a voting machine, the combination with a strip comprising longitudinally movable sections and two-armed locking dogs whose ends are adapted to engage different sections, of oppositely extending inter-engaging wedges, one of which is connected to the strip.

In testimony whereof I affix my signature in presence of two witnesses.

CHARLES C. ABBOTT.
